NUT SLITTER OR THE LIKE

Anna A. Miceli, 450 N. May St., Chicago, Ill.

Filed Nov. 16, 1962, Ser. No. 72,522

Term of patent 14 years

(Cl. D44—1)

FIGURE 1 is a perspective view of a nut slitter or the like showing my new design;

I claim:

The ornamental design for a nut slitter or the like, substantially as shown.
